UNITED STATES PATENT OFFICE.

JOHN KIEWICZ, OF HYDE PARK, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-STITCHING MACHINE.

1,073,244.

Specification of Letters Patent. Patented Sept. 16, 1913.

Application filed July 13, 1912. Serial No. 709,140.

To all whom it may concern:

Be it known that I, JOHN KIEWICZ, a citizen of the United States, residing at Hyde Park, in the county of Norfolk and State 5 of Massachusetts, have invented certain new and useful Improvements in Buttonhole-Stitching Machines, of which the following is a specification, reference being had therein to the accompanying drawing.

10 My invention relates to buttonhole stitching machines, and more particularly to the "under sewing mechanism" of a button hole sewing machine, the invention being shown applied for convenience to that type 15 of machine known to the trade as the "Reece" button hole machine wherein a stitch frame carrying the stitch forming mechanism on the one hand and a work clamp or support on the other hand, is relatively movable so as to enable the stitching 20 to be carried along the sides of the button hole and around its end or ends. Such stitch forming mechanism comprises usually an eye-pointed needle carrying the upper 25 thread and, below and opposed thereto, the so-called "complemental stitch forming mechanism" or "under sewing mechanism," which carries and operates an under thread in coöperation with the needle carrying the upper thread.

The principal object of the present invention is to improve the operation and the mechanical fitting of the under needle whose path of movement and surroundings present 35 certain difficulties, as will be herein-after explained.

Heretofore known under sewing mechanisms for button hole sewing machines have been complicated, including many 40 irregularly shaped and moving machine parts involving not only difficulty and expense in design and construction, but also in adjustment and repair. In machines of this class improvements of simplification 45 have been found both difficult and highly desired, not only because cheapening the construction of the mechanism, but rendering it more efficient and less likely to get into disorder.

50 The present improvements effect a substantial simplification of mechanism.

The further and more detailed objects hereof will be set forth in the following description or will be obvious to those skilled 55 in the art.

I will first refer to my preferred embodiment of the present invention, as applied to a type of mechanism in which the movements of the needle and looper are substantially the same as in U. S. Letters Patent 60 No. 695,039, granted March 11, 1902, upon the invention of W. W. Dixon, and I will thereafter point out the novel features in the claims.

In the accompanying drawings forming a 65 part hereof, Figure 1 is what may be termed a rear view in elevation of a mechanism embodying my present invention. In this view I have shown the upper portion of the circularly moving block or stock, which supports the under sewing mechanism and the parts carried thereby including the looper, the throat, the under needle and the fittings of the latter; the lower portion of the block and the remainder of the machine 70 being omitted as unnecessary for a disclosure of the present invention. Fig. 2 is a view similar to Fig. 1, but showing the under needle in its elevated rather than its depressed position. Fig. 3 is a left-hand elevation, that is to say looking toward the right-hand side of the parts shown in rear view in Fig. 1. Similarly Fig. 4 is a front elevation of the same parts shown in the other figures.

85 Similar characters of reference designate corresponding parts in the several figures of the drawings.

The clamp frame, the upper needle and bar, and the curb or cam casing may be as 90 in said prior Dixon patent, and are not illustrated herein. The stock or block 1 having the circular upper end 2 adapting it to receive at suitable times a circular movement, may be fitted and actuated in any proper 95 way. The lower part of the block 1 may be provided with thread tension devices, as in said prior patent, and since these and the path of the thread will be well understood, they are for clearness omitted. A throat 100 piece 3 is permanently fixed to the block 1, and its central aperture is disposed to properly receive the upper and under needles as they reciprocate in the process of sewing.

105 In machines of the class to which this invention refers, the under needle is designed to have a curved or substantially circular reciprocatory motion, and the under needle 4 hereof is adapted and fitted to the same end. Coöoperating with the curved needle 110

4 is a looper 5 whose construction, mode of operation and fittings may be substantially as in said prior Dixon patent; and those fittings forming *per se* no part of the present invention, will not be further referred to.

5 Preferably the needle 4 is attachable to and detachable from a distinct member which may be termed a needle carrier 6, and it is in fact the carrier that is fitted to receive the curved movements which are thereby imparted to the needle.

10 The movement of the needle 4 and carrier 6 is a simple oscillation in substantially the arc of a circle, causing the needle to first 15 pass upwardly through the button hole to a position above the fabric where it coöperates with the upper needle, the under needle then returning to a position beneath the fabric where it coöperates with both the 20 looper and the upper needle. In the Dixon patent the needle carrier is shown as a curved slide fitted to an arc-shaped slide-way or race, this construction serving to guide the needle in the arc of a circle, and 25 this manner of fitting has been largely employed despite the disadvantages of a curved race and slide, which are not only difficult to construct and keep in repair, but cause excessive resistance, friction and wear. As 30 will be clearly seen the present invention is contrary to the Dixon construction.

35 Considering the nature of machines of the present type and the essential motion of the curved lower needle from its position below to above the fabric, it will be understood that the center of oscillation of the needle must be at an elevated point, in fact substantially at or relatively close to the level of the fabric itself or the plate which 40 supports it during the sewing operation. The further the center of oscillation is displaced from the work, the less truly will the needle pass vertically through the button hole as it should. It must also be remembered that the under sewing mechanism 45 as a whole has to be swung bodily around at different stages of the formation of a button hole, and all of its parts during such movement must freely clear the fixed parts 50 of the machine so as to avoid accidental contact. An essential part 7 of the machine is shown for example in Fig. 1, which part has to be cleared as the under sewing mechanism 55 circularly shifts. For these various reasons it has heretofore been found impossible to provide a simple shaft fitting, whereby the needle may be simply swung about a shaft located at its proper or natural center, since such a shaft would have been prohibitive on 60 account of the interference above pointed out.

65 According to my present invention I have enabled the employment of a shaft or pivot for this purpose, by locating the actual axis or shaft at a substantially less distance from

the carrier than the theoretical center of the needle's arc of movement, and then bridging the space from the actual center to the carrier by a swinging arm pivoted upon the stock at such center, and then pivoting the 70 carrier to the other end of such swinging arm so that the needle instead of swinging about the actual center may be substantially caused to swing about the desired theoretical center. I prefer to locate a shaft at the 75 actual center, mount the swinging arm thereon and connect the needle carrier to such arm. By this arrangement the swinging arm constitutes a guiding means for one part of the carrier enabling the carrier to 80 be considered as a link, having suitable guiding means at another point as well, so that the two guiding means may coöperate to give the needle the desired arc movement.

85 The stock 1 has an inclined extension 8, the inclination being to enable the upper and lower needles to operate without conflict, and on this extension 8 is located the axis pivot or shaft 9 for the swinging arm 10. The carrier is shown pivoted at 11 to the 90 swinging arm 10, although it might be otherwise connected thereto with equivalent results.

95 Considering the carrier 6 as a link, the arm 10 affords one guiding means connected at point 11. In order that the link shall be positively guided, there should be another guiding means which might take different forms, but is shown as consisting of a cam and stud connection, the stud 12 preferably 100 being secured to the link or carrier, and the cam 13 being constituted as a slot formed in the extension 8. This cam and stud may be said to be a superior equivalent of a second swinging arm. The two guiding means 105 thus described are shown so arranged that the needle in oscillating will describe an arc which is substantially the arc of a circle whose center is not at the pivot 9, but at a considerably higher point, which upon the 110 drawing would come within the area of the fixed machine part 7. This result is effected herein by constituting the cam 13 not in a concentric form but rather, as shown, in the form of an eccentric slot so that there 115 will be caused a slight relative angular movement, as between the arm 10 and the carrier 6, during operation.

120 I prefer that the swinging arm 10 be secured upon shaft 9 so that by oscillating the shaft the carrier is caused to move as desired. Fig. 3 indicates a convenient means of fitting the shaft 9, one end of which is journaled in the extension plate 8, and the other end in an extension 14 produced 125 for convenience as a part of the extension 8. This arrangement gives the shaft 9 a certainty of action and steadiness of position so that there can be no lost motion in the oscillation of the needle. Secured upon the 130

shaft 9 by means of its hub 15 is shown an actuating arm 16 extended as clearly shown in Figs. 1 and 2 in such direction as to enable it to be swung from one limit of its movement to the other by means of a downwardly extending actuating bar or connection 17, which may be considered as an intermediary link between the actuating arm 16 and an upwardly and downwardly moving actuator such as the rod 59 of said prior Dixon patent. In view of the actuating arm 16 moving in an inclined plane, I prefer to provide a universal connection 18 between the arm 16 and the link 17.

15 A consideration of the fittings of the needle and carrier and the movement thereof indicated by the respective positions of Figs. 1 and 2 will show that the needle is thereby caused to travel in the substantial 20 arc of a circle (strictly speaking it departs from a circular arc) of a fairly long radius of oscillation whose center is so high as to coincide with parts of the machine external to the under sewing mechanism, while the 25 arm 10 is of substantially shorter length than the needle's aforesaid substantial radius of oscillation. The arm 10 forming one guiding means, the other guiding means, namely the stud and cam, may be said to 30 constitute a device actuating upon the needle carrier to cause the needle to swing with a substantial radius which is greater than the length of the arm. If the carrier were rigidly secured to the arm, the needle would 35 necessarily oscillate about shaft 9, but being pivoted the additional guiding device is enabled to modify the needle's movement in the desired manner.

The improvement may be briefly restated 40 as follows. The link 10 and the cam and stud 12, 13 are in effect two distinct guiding devices fitted at separated points upon the carrier 6, and together constituting the fittings enabling the carrier to be reciprocated upon the stock 1 as described, so as to 45 carry the under needle from below to above the level of the work and return in a curved path about a center, which is imaginary rather than actual, located substantially at 50 the work level. Thereby the under needle is enabled to constantly coöperate with an upper needle, and at the same time the stock, carrying the under sewing mechanism, is enabled to shift as may be necessary, for 55 example by oscillation on its own vertical axis as explained.

By the under sewing mechanism above described, it will be seen that the objects and advantages hereinbefore recited are accomplished in an effective manner, and other advantages will be apparent to those conversant with the art. Since the details hereof may be variously modified without departing from the principles of the present 65 improvement, I do not wish to be limited

thereto except as may be specified in the appended claims.

What I claim and desire to secure by Letters Patent is:

1. In a button hole sewing machine an under sewing mechanism comprising in combination a stock, a swinging arm pivoted upon said stock, an oscillating needle carrier pivoted to said arm, a stud on said carrier engaging a slot on said stock, and means to cause said carrier's movements.

2. In a button hole sewing machine an under sewing mechanism comprising in combination a stock, a needle carrying link, a swinging arm pivoted to one part of said link and pivoted upon said stock, and a cam and stud for guiding another part of said link.

3. In a button hole sewing machine an under sewing mechanism comprising in combination a stock, a needle carrying link, a swinging arm pivoted to one part of said link and pivoted upon said stock, and means for guiding another part of said link, said guiding means comprising a stud on said link engaging an eccentric slot in said stock.

4. In a button hole sewing machine an under sewing mechanism comprising in combination a stock, a needle carrying link, a swinging arm pivoted to one part of said link and pivoted upon said stock, and means for guiding another part of said link, said guiding means comprising a stud on said link engaging an eccentric slot in a stationary extension of said stock.

5. In a sewing machine of the type having coöoperating upper and under needles, an under sewing mechanism including in combination, a stock shiftable during the sewing operations, an under needle carrier, and fittings for rendering said carrier reciprocable upon said stock to carry an under needle from below to above the level of the work and return in a curved path about an imaginary center located substantially at the work level, said fittings comprising two distinct devices fitted at two separated points upon said carrier both below such center of reciprocation.

6. In a sewing machine of the type having coöoperating upper and under needles, an under sewing mechanism including in combination, a stock shiftable during the sewing operations, an under needle carrier, and fittings for rendering said carrier reciprocable upon said stock to carry an under needle from below to above the level of the work and return in a curved path about an imaginary center located substantially at the work level, said fittings comprising two distinct devices fitted at two separated points upon said carrier, at least one of said devices being a stud and cam connection between the stock and carrier.

7. In a sewing machine of the type hav-

130

ing coöoperating upper and under needles, an under sewing mechanism including in combination, a stock shiftable during the sewing operations, an under needle carrier, and fittings for rendering said carrier reciprocable upon said stock to carry an under needle from below to above the level of the work and return in a curved path about an imaginary center located substantially at the work level, said fittings comprising two distinct devices fitted at two separated points upon said carrier, at least one of said devices being a link pivoted directly to both the stock and carrier.

8. In a sewing machine of the type having coöoperating upper and under needles, an under sewing mechanism including in combination, a stock shiftable during the sewing operations, an under needle carrier, and fittings for rendering said carrier reciprocable upon said stock to carry an under needle from below to above the level of the work and return in a curved path about an imaginary center located substantially at the work level, said fittings comprising two distinct devices fitted at two separated points upon said carrier, at least one of said devices being a link pivoted to the stock and carrier, and means including a fixed-position shaft to which said link is secured, for effecting the oscillation of said link and carrier.

9. In a sewing machine of the type having coöoperating upper and under needles, an under sewing mechanism including in combination, a stock shiftable during the sewing operations, an under needle carrier, and fittings for rendering said carrier reciprocable upon said stock to carry an under needle from below to above the level of the work and return in a curved path about an imaginary center located substantially at the work level, said fittings comprising two distinct devices fitted at two separated points upon said carrier, both below such center of reciprocation, and at least one of said devices being a link pivoted directly to both the stock and carrier, and having an effective length substantially shorter than the carrier's effective radius of oscillation.

10. In a sewing machine of the type having coöoperating upper and under needles, an under sewing mechanism including in combination, a stock shiftable during the sewing operations, an under needle carrier, and fittings for rendering said carrier reciprocable upon said stock to carry an under

needle from below to above the level of the work and return in a curved path about an imaginary center located substantially at the work level, said fittings comprising two distinct devices fitted at two separated points upon said carrier, one being a link pivoted to the stock and carrier and the other being a stud and cam connection between the stock and carrier.

11. In a sewing machine of the type having coöoperating upper and under needles, an under sewing mechanism including in combination, a stock shiftable during the sewing operations, an under needle carrier, and fittings for rendering said carrier reciprocable upon said stock to carry an under needle from below to above the level of the work and return in a curved path about an imaginary center located substantially at the work level, said fittings comprising two distinct devices fitted at two separated points upon said carrier, one being a link pivoted to the stock and carrier and the other being a stud and cam connection between the stock and carrier, said link having an effective length substantially shorter than the carrier's effective radius of oscillation; and means including a shaft to which said link is secured, for effecting the oscillation of said link and carrier.

12. In a sewing machine of the type having coöoperating upper and under needles, an under sewing mechanism including in combination, a stock shiftable during the sewing operations, an under needle carrier, and fittings for rendering said carrier reciprocable upon said stock to carry an under needle from below to above the level of the work and return in a curved path about an imaginary center located substantially at the work level, said fittings comprising two distinct devices fitted at two separated points upon said carrier, one being a link pivoted to the stock and carrier and the other being a stud and cam connection between the stock and carrier, said link being pivoted near the end of the carrier from which the needle projects, and the cam and stud being connected near the opposite end thereof.

In testimony whereof I affix my signature in presence of two witnesses.

JOHN KIEWICZ.
